STEERING WHEEL

Elmer C. Kiekhaefer, Cedarburg, and Carl Knuth, Fond du Lac, Wis., said Carl Knuth assignor to Kiekhaefer Corporation, Cedarburg, Wis., a corporation of Wisconsin

Application February 20, 1956, Serial No. 40,240

Term of patent 14 years

(Cl. D14—30)

FIG. 1.

FIG. 2.

FIG. 3.

Fig. 1 is a plan view of a steering wheel embodying our new design;

Fig. 2 is a section view taken along line 2—2 of the design shown in Fig. 1; and

Fig. 3 is a section view taken along line 3—3 of the design shown in Fig. 1.

The characteristic features of our design for the steering wheel disclosed reside in the central hub portions having the configuration shown.

We claim:
The ornamental design for a steering wheel, as shown and described.
